UNITED STATES PATENT OFFICE

FRANK S. HYATT, OF BROOKLYN, NEW YORK, ASSIGNOR TO BRASS GOODS M'F'G. CO., OF BROOKLYN, NEW YORK, A CORPORATION OF NEW YORK

BOTTLE-WASHING DEVICE

Application filed December 7, 1927. Serial No. 238,258.

This invention relates to improvements in bottle-washing apparatus, it being a primary object of the invention to provide an economical, portable apparatus intended 5 particularly for domestic use.

It is a further object to provide a more perfectly operating device of this character.

More specifically the invention contemplates a rigid supporting and liquid-supplying structure which can be connected directly to a faucet and which is provided with means for engagement by a bottle or other article to be washed so that by means 15 of a slight pressure upon the bottle or other article itself the cleansing fluid may be supplied to the interior of the bottle.

These and other objects will appear more fully from the following description when 20 considered in connection with the drawings in which:

Fig. 1 is a vertical sectional view of the apparatus in its operative position.

Fig. 2 is a similar view of a portion of the 25 apparatus showing the closure means in closed position.

Fig. 3 is a transverse sectional view taken on the line 3—3 of Fig. 1.

Fig. 4 is a front elevation (partly in section) of a portion of the device.

Referring in detail to the drawings:

1 indicates a goose-neck shaped rigid supply pipe one end of which is rotatably connected to the base 2 of a screw-threaded coupling 3 whereby the coupling may be screwed on any conventional form of spigot without rotating the pipe 1. The coupling 3 preferably carries a compressible washer 5 whereby a close and water-tight connection between 40 the parts may be obtained. The other open end of the pipe 1 extends upwardly into a hollow body 6 and is provided with a flange 7 acting as a stop to prevent said pipe from being inserted too far within said body.

45 The pipe 1 above said flange 7 also carries a pin 8 adapted to be passed through a notch 9 formed on the enlarged nipple forming portion of the hollow body 6 and when the head 6 is rotated with respect to 50 the pin 8 the pin is passed into the interior

of the nipple forming enlargement of the head 6, thus providing a detachable and convenient connection between the head 6 and pipe 1. This readily detachable connection between the two parts of the device provides for their easy and convenient cleansing and shipping. The body 6 interfits with a head 10 with which it preferably telescopes and to which it is attached in any desirable manner, both parts preferably being 60 formed of sheet metal.

The head 10 is formed with a neck 11 slidably receiving therein a discharge tube 12. The lower end of said tube is provided with a closing plug 13 carrying a rubber gasket 14 adapted to be compressed against the inner wall of the head 10 by the action of a spring 15. Said spring engages the lower side of the plug 13 and the inner wall of the body 6 at or adjacent its lower end whereby 70 the discharge tube 12 is normally held in closed position within the neck 11 or that shown in Fig. 2. Adjacent its lower end the discharge tube 12 is provided with a plurality of openings 16 which are normally 75 closed by the neck 11 when the tube is in normal or raised position. The discharge tube also carries a pin 17 preferably extending therethrough and providing a suitable rest for engagement by the neck of the bottle 18 as shown in Fig. 1 whereby the tube will extend a substantial distance into the interior 80 of the bottle.

The operation of the device will readily be understood from the above description. 85 It will be obvious that when the coupling 3 is screwed onto the spigot 4 and water or other liquid is supplied to the pipe 1 under pressure the liquid will be forced up into the body 6. When the bottle neck 18 has 90 been introduced over the rest or pin 17 pressure upon the bottle will cause the lower end of the tube 12 and its plug 13 to move downwardly within the body 6 against the action of the spring 15 whereby the openings 95 16 will be uncovered. The water or other liquid under pressure will then flow through the openings 16 and upwardly through the discharge tube 12 and into the bottle 18 to cleanse the same. When pressure upon the 100

rest or pin 17 has been released by removal of the bottle 18 or otherwise the spring 15 together with the pressure of the water within the body 6 will automatically cause the tube 12 to move upwardly into normal position to close the openings 16 as previously described.

The same connection or nipple on the lower end of the portion 6 of the head and which is slotted as at 9 enables the apparatus 6, 10, 12, etc. to be used on the pipe 1 as in Fig. 1 or to be separated therefrom, inverted and used with a hose or otherwise in filling bottles as will be readily understood.

It will be seen from the above description that I have provided a bottle-washing apparatus which may be economically constructed of sheet metal in practically all the parts thereof, which may be easily and cheaply manufactured and shipped and which will operate satisfactorily for its intended purpose.

What I claim as my invention is:

1. In a bottle-washing apparatus, a hollow body composed of a plurality of sheet metal members each having similarly constructed enlarged head forming portions telescoped and held in secure frictional engagement throughout said enlarged portions, one of said members including an elongated bearing portion, a discharge tube slidably received within said bearing portion and formed with a plug co-acting with said body when said tube is moved outwardly therefrom for closing off said body from said tube, and spring means for normally maintaining the parts in closed position.

2. In a bottle-washing apparatus, a supply pipe, a coupling attached to one end thereof, a hollow body received by the other end of said pipe and provided with a notch in the lower wall thereof, a pin on said pipe for entering said notch whereby said body and pipe may be detachably connected together, a spring-pressed discharge tube received by said body and bottle-receiving means carried by said discharge tube.

Signed at Brooklyn, in the county of Kings and State of New York this 11th day of November A. D. 1927.

FRANK S. HYATT.
